UNITED STATES PATENT OFFICE.

JOSEPH E. DALLON, OF BROOKLYN, NEW YORK.

DESIGN FOR AN ASH-RECEIVER, &c.

SPECIFICATION forming part of Design No. 19,047, dated April 16, 1889.

Application filed January 28, 1889. Serial No. 297,832. Term of patent 3½ years.

To all whom it may concern:

Be it known that I, JOSEPH E. DALLON, a citizen of the United States, residing at Brooklyn, in the county of Kings and State of New York, have invented and produced a new and original Design for Ash- Receivers, Match-Safes, &c.; and I do declare the following to be a full, clear, and exact description of the same, reference being had to the accompanying drawing, forming a part thereof, which represents my novel design in elevation.

The design consists of miniature representations of a shovel, a tongs, and a poker, constituting a tripod converging at the top in an apex, and a coal-scuttle depending from the tripod between the limbs thereof.

1 denotes the miniature representation of a scuttle, which is of ordinary form, and is provided with the usual handle, 2.

3 denotes the miniature representation of an ordinary fire-shovel, 4 the miniature rep-

resentation of a tongs, and 5 the miniature representation of a poker. The upper ends of the shovel, tongs, and poker are secured together at the apex, forming a tripod, and the shovel is suspended between the limbs thereof by a chain, 6.

Having thus described my invention, I claim—

The design for ash-receivers herein shown and described, the same consisting of miniature representations of a shovel, tongs, and poker, constituting a tripod converging at the top in an apex, and a coal-scuttle depending from the tripod between the limbs thereof. 35

In testimony whereof I affix my signature in presence of two witnesses.

JOSEPH E. DALLON.
